UNITED STATES PATENT OFFICE.

BRUCE H. TINGLEY, OF CINCINNATI, OHIO, ASSIGNOR TO THE DALTON ADDING MACHINE COMPANY, OF CINCINNATI, OHIO, A CORPORATION OF OHIO.

CROSS-TABULATING CARRIAGE FOR ADDING MACHINES.

Application filed November 25, 1922. Serial No. 603,146.

To all whom it may concern:

Be it known that I, BRUCE H. TINGLEY, a citizen of the United States, residing at Cincinnati, in the county of Hamilton and State of Ohio, have invented certain new and useful Improvements in Cross-Tabulating Carriages for Adding Machines, of which the following is a specification.

This invention relates to adding machine mechanism designed for the purpose of automatically shifting the platen across the machine in conformity with the column arrangement of the sheet to be imprinted and with due regard to the nature of the data to be imprinted in each column.

In the particular class of bookkeeping work for which the present mechanism is designed, it is essential that some of the items on the same horizontal line should be listed but not added, and also essential that some items be subtracted. The present invention makes provision for automatically throwing the adding wheels into and out of train in conformity with the column relation of the carriage and of automatically operating the subtraction mechanism at the proper interval, so that it is unnecessary for the operator to manually adjust the machine during the imprinting of the several co-related items.

The invention further relates to the means which are provided for causing the paper carriage to automatically move toward the left from column to column each time the handle is operated without actuating the mechanism provided for line spacing the paper, so that items may be added, subtracted, or recorded across the sheet from left to right, and a total taken without the necessity for manipulation of the paper carriage.

The invention further relates to the provision of detachable cams which may be adjusted by the operator to function in selected columns, so that the adding mechanism will be disabled when the paper is in alignment with the intended column or columns.

A further object of the invention is to provide means whereby the automatic cross tabulating movement of the paper carriage, the automatic non-adding of items, the automatic subtraction mechanisms, and all other special features, may be normalized by the operator, so that the machine will function

in any position as an ordinary adding machine.

The invention finally relates to the co-ordination of the several mechanisms above mentioned with the usual mechanisms of a standard type of adding machine, so that said mechanisms may be applied to standard types of adding machines without substantial change or modification of the usual standard mechanisms and without impairment of their natural or normal functions. The accompanying drawings illustrate the mechanism applied to a Dalton adding machine and so much thereof is illustrated as may be required for a clear understanding of the special features of the present invention, although it will be understood that it is not the intention to limit the invention to any particular make or style of adding machine.

In the drawings:

Fig. 1 is a longitudinal sectional elevation of a Dalton adding machine illustrating in part the various important units such as the adding and printing racks, movable stop carriage, numeral key levers, main shaft, and the automatic cross tabulating carriage mechanism of the present invention;

Fig. 2 is a side elevation of the mechanisms which control the functioning of the subtraction mechanism;

Fig. 3 is a plan view of the subtracting cam;

Fig. 4 is a plan view of the automatic subtraction rock shaft in condition for operation;

Fig. 5 is a similar view of this mechanism normalized and inoperative;

Fig. 6 is an elevation partly in section of the automatic subtraction rock shaft and associated parts;

Fig. 7 is a plan view of the cross tabulating escapement mechanism with the normalizing device set in normalized position;

Fig. 8 is a side view of the same mechanism in the same position;

Fig. 9 is a similar view showing the position of the parts when the paper carriage escapement is released for shifting the paper carriage by hand;

Fig. 10 is a plan view of the cross tabulating escapement mechanism in the operative position assumed when the handle is pulled to its forward position;

Fig. 11 is a side view of the same mechanism in the same position;

Fig. 12 is a side view of the normalizing device set in position to permit operation of the special features of the present invention and with the adding parts in the position assumed before the operation thereof;

Fig. 13 is a similar view showing the non-adding parts in operative position for cross tabulating;

Fig. 14 is a front view of the normalizing knob and detent in the position shown in Figs. 12 and 13;

Fig. 15 is a side view of the normalizing device and associated parts in the position assumed to normalize the operation of the adding machine and disable the operation of the special tabulating features;

Fig. 16 is a front view of the normalizing knob and detent in the position shown in Fig. 15;

Fig. 17 is a side view of the non-adding cam in relation to the non-adding mechanism when the machine is normalized; and

Fig. 18 is a plan view of the detachable non-adding cam and its retaining mechanism.

The mechanism of the present invention is applied to an adding machine of well known type including adding racks 20, type bars 21 provided with type 22, a platen 23, hammers 24, a stop carriage 25 provided with stops 26 and numeral keys 27 provided with tappets 28 adapted to contact with and set the stops. The mechanism also includes a bank of adding wheels 29 and a main operating shaft 30 actuated by a handle 30*, in the usual manner.

The above mechanisms are well understood and detailed description thereof is deemed unnecessary. The platen 23 is mounted within a paper carriage comprising end plates 31 which are connected by an upper front cross rod 32, a lower cross plate 33, an intermediate lower cross rod 34 and an upper cross bar 35. The carriage plates are also connected by a cross frame 36 provided with upper and lower shoulders 37 and 38 which embrace a fixed guide rail 39, the shoulders and rail being correspondingly grooved to afford runways for upper and lower sets of balls 40, the track and ball arrangement serving to reduce friction and permit the carriage, when released, to travel easily across the machine from right to left under the tension of a suitable spring, not shown, in a manner well understood in the present art.

The cross frame 36 has secured to its top an escapement bar 41 (see Figs. 7 and 10), which bar is provided on its rear edge with a plurality of stop teeth 42 spaced to conform to the intended column arrangement of the page adapted to be imprinted by the

mechanism. The escapement bar is designed to co-operate with upper and lower dogs 43 and 44 respectively. The lower dog is fixedly secured to the under side of a square rock shaft 45 which is journaled at its ends 70 between the ears 46 of a bracket plate 47 fixedly secured to the frame of the machine at the rear of the paper carriage. The upper dog is slidably mounted upon the lower dog, being provided with an elongated slot 75 48, which receives a headed pin 49 which co-acts with a stud 50 to guide the upper dog in its sliding movements across the upper face of the lower dog.

The upper dog has connected thereto the spring 51 which is secured at one end to a stud 52 on the rear end of the upper dog, and on the other end to a hook 53 protruding from the plate 54 which is secured to the upper face of the rock shaft 45. 80 The tension of this spring acts in a direction counter to that of the spring which controls the escapement of the paper carriage, but since the spring 51 is of less tension, it will be distended when subjected to the stronger tension of the escapement spring.

The dogs 43 and 44 are provided with teeth 55 and 56 respectively, which teeth are aligned with one another when the upper dog is forced to the left, as in Fig. 7, by the contact of one of the escapement bar teeth with the tooth 55 on the upper dog. When, however, the rock shaft 45 is rocked upwardly, as indicated in Fig. 11, the tooth of the upper dog will be disengaged from the escapement bar tooth, but without releasing effect thereon, since the lifting of the dogs will bring the tooth of the lower dog into engagement, but this lifting action will, by disengaging the tooth of the upper dog, allow the latter to spring to the right, as in Fig. 10, under the tension of the spring 51, so that upon a return movement 95 of the rock shaft, the escapement bar tooth will be definitely released and the carriage moved one step to the left and until the next succeeding tooth engages the tooth of the upper dog and carries the same from its free position shown in Fig. 10 to its final or resting position shown in Fig. 7. The rocking movements of the shaft 45 are effected through the action of the following mechanisms. The rock shaft 45 has rigidly attached to its left end a crank arm 57 which has pivoted to its lower end a rocking arm 58 provided near its upper end with a stud 59 which engages the forward edge of the arm 57 and is held in contact therewith through the tension of the spring 60 which is connected at its rear end to the rocking arm and at its forward end to a fixed portion of the carriage cross frame 36, and also by the tension of the spring 61 which connects the upper end of 100 105 110 115 120 125 130

the rocking arm with an adjacent portion of the arm 57.

While the carriage is stationary, the escapement dogs are held in lower position by the action of a cam 62 mounted on a shaft 63 which likewise furnishes a mounting for the type carriers, which shaft is rocked by the swinging of an arm 64 connected by a link 65* with a portion of the handle controlled 10 mechanism (not shown), so that on the forward movement of the handle the shaft 63, as viewed in Figs. 8 and 9, will be moved in a counter-clockwise direction which will turn the cam 62 from the position shown in Fig. 15 8 to the position shown in Fig. 11. The cam 62 engages a roller 64* on the swinging arm 58, so that as the cam is lowered, and the roller released from the elevated portion 20 of the cam, the spring 60 will draw the arms 57 and 58 forwardly with a consequent lifting of the escapement dogs, unless this movement is blocked by mechanisms presently to be described. Upon the return movement 25 of the operating handle, the action of the cam will lower the dogs after releasing the previously engaged tooth of the escapement bar.

The above operation takes place regularly in the manipulation of the cross tabulating 30 mechanism, but when it is desired to normalize the action of the machine and hold the carriage in fixed relation, means are provided for rendering ineffective the cam releasing action just described.

35 The shaft 63 has loosely mounted thereon a normalizing cam 65 which, when elevated as in Fig. 8, will engage the roller 64, irrespective of the position of the cam 62. The normalizing cam 65 has pivoted thereto a link 40 66, as shown in Figs. 1 and 15, which is pivoted at its lower end to a normalizing lever 67 which, in turn, is pivoted at its center to a cross shaft 68. The forward end 69 of the normalizing lever is bifurcated to receive a 45 tongue 70 struck rearwardly from the upper arm of a bell crank lever 71 pivoted at its elbow to a bracket 72 secured to the front of the machine frame 73*, as best shown in Figs. 14, 15 and 16.

50 The bell crank lever 71 carries a normalizing knob 73, located within convenient reach of the operator, and a stud 74 engaging a notched spring detent 74* adapted to hold the knob either in the position shown in Fig. 14, 55 which may be termed the "tabulating position", or in the position shown in Fig. 16, which may be termed the "normalizing position". With the normalizing knob thrown to the left, as in Fig. 14, the upper end of the bell crank 71 will be lifted, thereby lifting the forward end of the normalizing lever 67 which serves to draw down the link 66 and thereby move the normalizing cam 65 out of contact with the roller 64*, as indicated in Fig. 11, so that the roller will be free to

swing forward when released by the rocking of the cam 62 to effect an escapement of the carriage in cross tabulating. When, however, the normalizing knob is thrown to the right, as in Fig. 16, an upward thrust of the link 66 will be occasioned, and this will have the effect of throwing the cam 65 upwardly, so that the roller 64 will be blocked and the escapement mechanism disabled.

At times it may be desirable to shift the carriage manually and this may be effected by the depression of a thumb lever 75 which is rigidly secured to the right hand end of a rock shaft 76 which is journaled between the end plates of the paper carriage, and is provided with a rearwardly extending elongated flange 77 which underlies the tip of the bent finger 78 secured to the rock shaft 45 irrespective of the transverse position of the carriage, so that the depression of the thumb lever against the tension of the spring 79 will tilt the rock shaft, as in Fig. 9, and thereby lift both the upper and lower escapement dogs above the plane of the escapement bar, allowing the carriage to be 90 manually adjusted to the desired position.

At certain points in the cross travel of the carriage it is necessary to make provision for actuating the subtraction mechanisms, and for this purpose the carriage is provided with a cam plate 80 which is adjustably supported from the rear upper cross bar 35 (see Figs. 1 and 2). The cam plate is provided at a suitable point with a rearwardly extending cam 81, best shown in Fig. 3, which cam is adapted to co-act with a roller 82 upwardly projecting from an arm 83, which arm merges into a hub 84 bored to receive the upper end of a vertical shaft 85 which has entered thereto a headed stud 86. The hub is shouldered at the point 87 to afford a point of contact for the lower end of a spring 88 which surrounds the headed stud 86. This arrangement permits the hub 84 to be slightly elevated by means 100 of a knurled knob 89.

The hub 84 co-acts with a ring 90 which is keyed to the shaft 85, and, as indicated in Fig. 2, the ring is provided with a tooth 91 which co-acts with either of a pair of notches 92 formed in the lower face of the hub, so that the latter may be turned to lock with the roller 82 in its forward position to engage the cam 81, as in Fig. 2, or to a rearward position which throws the roller out of the line of movement of the cam. The vertical shaft 85 has pinned thereto an inwardly projecting arm 93 which is entered through a slot 94 in a link 95 which is pivoted at its rear end to a rocking lever 96 fulcrumed at the point 97 in a fixed plate 98 and held retracted by the tension of a spring 99.

The forward end of the link 95 connects with the upper end of a lever 100 mounted 120

on the shaft 68. The lower end of the lever is connected by means of a link 102 with a crank arm 103 pinned on a rock shaft 104. The rock shaft also carries a forwardly 5 projecting arm 105 provided with a laterally protruding stud 106 which is engaged by the upper edge of a finger 107 secured to and rearwardly projecting from the upper end of a subtraction key lever 108, 10 which finger is hooked over and pivoted upon a fixed shaft 109 near the front of the machine. The finger works against the tension of the spring 110, and when the subtraction key is depressed, a forward 15 swinging movement will be imparted to the arm 93 through the train comprising the arm 105, shaft 104, arm 103, link 102, lever 100 and link 95. The subtraction key lever 108 engages the forward end of a lever arm 111 which is likewise pivoted upon the shaft 109, and between the subtraction key lever and the lever arm is a lost motion connection consisting of pins 112 and slots 113, the arrangement being such that when motion 20 is manually imparted to the subtraction train from the subtraction key, the lever arm 111 will be swung by engagement of the pins and slots, but when the subtraction train is operated automatically by the 25 cross movement of the paper carriage, the movements of the train will not be transmitted to the key. The arm 111 likewise is engaged by the stud 106 on its under side, and its upper end extends to a point immediately 30 behind a stud 114 carried by a finger 115 at the forward end of a draw bar 116 guided by a stud 117 working in a slot 118.

The rear end of the draw bar 116 is provided with a slot 119 which receives a stud 120 carried by the lower arm 121 of a character selector 122, a spring 123 affording the connection between the draw bar and the arm 121. The subtraction mechanism proper does not constitute a part of the present invention, the same being fully described in Patent No. 1,430,088 dated September 26, 1922, but the present invention is directed rather to the train of mechanisms employed for imparting the necessary movements of the subtracting mechanisms through the escapement of the paper carriage. It is, therefore, deemed unnecessary to describe the subtraction mechanism in detail, it being understood, however, that it is set in motion either by the depression of the subtraction key lever or by a forward thrust imparted to the link 95 by a forward swinging motion of the arm 94, and when imparted in the latter manner will be effected through the medium of the lever 100, the link 102, arm 103, shaft 104, arm 105, stud 106, arm 111, stud 114, draw bar 116, spring 123, and character selector 122. The 55 lost motion connection afforded by the pins

112 and slots 113 enable the above movements to be effected without imparting movement to the subtraction key lever.

When the mechanism is used for tabulating, it is necessary that certain items be 70 listed but not added, and in order to disable the adding mechanism, when the paper carriage is in certain selected column positions, the following mechanism is provided: To the lower forward cross bar 33 is secured a cam plate 124 illustrated in detail in Fig. 18, which cam plate is adjustable to any desired position along the cross bar 33. The latter is provided throughout its length with a series of perforations 125 of size 75 to have entered therethrough a pair of headed studs 126 projecting upwardly from the cam plate. These studs co-act with a slide bar 127 which is guided between guide studs 128 two of which are 80 shown in Fig. 18. The slide bar is provided with a plurality of key hole slots 129, the enlarged portions of which are of a size to permit the heads of the studs 126 to be projected therethrough when said enlargements are in register with the perforations 85 125. When, however, the slide bar is brought to the left, as in Fig. 18, the reduced portions of the key hole slots will engage the studs 126 behind the heads thereof, and hold the cam plate in fixed relation.

A spring 129^a is provided to normally hold the slide plate in locking relation, and a push button 130 projects outwardly from the end of the slide plate through the adjacent end plate 31 of the carriage to permit pressure to be applied to move the slide plate to releasing position. The cam plate is provided in its rear edge with a depression 131, and the plate as a whole co-acts 90 with a roller 132 mounted upon the upper end of the lever arm 133 which is pivoted at its elbow to a bracket 134 secured in fixed relation to the frame of the machine at a point immediately below the forward 95 portion of the carriage.

The lever arm 133 is provided at its rear lower end with a foot 135 which is adapted to engage a stud 136 on a lower arm 137, which arm is connected by means of a spring 138 with a lower finger 139 depending from the lever arm 133, the arrangement being such that, as the elevated portion of the cam plate 124 sweeps across the roller 132, the latter will be moved to the rear as in Fig. 13 throwing the finger 139 forwardly and exerting a spring tension which moves the lower arm 137 forwardly. The lower arm is positioned to engage a roller 139^a on a slide plate 140 which is provided with a depending lug 141 which engages a stud 142 on the upper portion of a bell crank lever 143 mounted on a cross shaft 144. The lower forward end of the said bell 110 115 120 125 130 135 140 145 crank lever is provided with a stud 145

- which, when in lowered position as in Fig. 1, serves to disable the train of mechanism 146 which normally serve to lift the adding wheels into engagement with the racks on the return movement thereof. Since the particular construction of this train of mechanism forms no part of the present invention, it is not deemed necessary to describe the same in detail.
- 10 The lower arm of the bell crank is normally held in raised position by means of a spring 147 secured to a fixed bracket 148, but this spring is of less tension than the spring 138, so that when the latter is drawn 15 forwardly by the movement of the finger 139, the movement will serve to stretch the spring 147 without elongating the spring 138. The mechanism above described will operate in the manner stated whenever movement of the carriage serves to bring an elevated portion of the cam plate into register with the roller, unless said movements are blocked by mechanism controlled by the normalizing knob. When the latter is moved to the position illustrated in Figs. 15 and 16, the depression of the normalizing lever 67, through the medium of a link 149, crank arm 150, and shaft 109, serves to impart a rearward rocking movement to 20 a bifurcated rock arm 152 which at its upper bifurcated end engages a stud 153 on a normalizing slide plate 154. The slide plate is provided with a pair of slots 155 which receives headed studs 156 and 139. 25 outwardly protruding from and carried by the slide plate 140, the arrangement being such that when the normalizing slide plate 154 is moved to the rear as in Fig. 15, the studs 156 and 139 will occupy positions 30 at the extreme forward ends of the slots 155, so that further forward movement of the slide plate 140 is blocked. In these circumstances, a rearward rocking of the arm 133 will simply have the effect of imposing 35 tension on the spring 138 without imparting movement to the lower arm 137, so that the adding mechanism will not be disabled despite the travel of the carriage to the left.
- 40 During the tabulating operations, it is necessary to disable the mechanism normally employed for rotating the platen in line spacing, and the following means are provided for this purpose: The normalizing slide plate 154 is provided on its upper edge 45 near its rear end with a cam elevation 157 which co-acts with a roller 158 on a block arm 159 which is pivoted on the shaft 68, so that when the slide plate is drawn forwardly, as in Fig. 13, for tabulating, the block arm 50 will be lifted and brought into the path of travel of a swinging arm 160 provided with a stud 161 which on the forward swing of the arm 160 will engage the rear end of the block arm and prevent continued movement 55 thereof. This blocking of the arm 160
- which is mounted on the shaft 162 serves to render ineffective the line spacing mechanism which depends for its actuation upon a full movement of the arm 160. The line spacing mechanism is of the character commonly employed for such purpose, and being well understood in the art, it is not deemed necessary to illustrate or describe the same in detail.
- 60 In operation, when it is desired to utilize the tabulating device of the present invention, the normalizing knob will be thrown to the left, as in Figs. 13 and 14, with a view of continuously disabling the line spacing mechanism, of disabling the adding mechanism at the intended column positions, and of permitting the escapement mechanism to act automatically with each movement of the operating handle. With the knob in this position, the subtraction mechanism is 65 also free to operate at the intended period in the travel of the carriage, provided the adjustment of the roller 82 is such as to co-act with the cam 80 on the carriage. With the parts thus adjusted, each operation 70 of the handle will effect a release of the escapement allowing the carriage to move one step to the left without line spacing, so that the various items can be cross tabulated and either accumulated or omitted 75 from the accumulation depending upon the adjustment of the cam, provided for disabling the operation of the adding wheels.
- 80 When it is desired to normalize the operation of the machine, the carriage may be adjusted to the desired position by manually lifting the escapement dogs, and allowing the carriage to move to the left, after which an adjustment of the normalizing knob to the position indicated in Fig. 16 will adjust the various mechanisms so as to permit line spacing and accumulating, but will 85 permanently block the operation of the escapement dogs, so that the carriage will maintain a definite cam position. The adjustment of the normalizing knob to normalizing position, as in Fig. 15, will prevent the cam 124 from actuating the adding wheel disabling mechanisms, irrespective of the relation of the cam 124 to the roller 132, so that it is not necessary to remove or readjust the cam during such normal operation, although such removal or readjustment may be desirable if the relation of the cam to the roller happens to be such 90 as to continuously retract the roller and impose a continuous tension on the spring 138. The arrangement of the automatic subtraction train is such that it interferes in no way with the normal use of the subtraction key lever, so that the two mechanisms may be interchangeably employed, although where such subtraction is required in a given column in the tabulating operation, it is desirable to adjust the subtraction 95

cam plate 80 to the desired column position and adjust the subtraction actuating roller 82 into co-operative relation with the cam, so that subtraction will automatically take place on each return of the carriage to the intended column.

The mechanisms above described are adapted to be applied to adding machines of standard type without substantial change 10 or modification of the regular standard equipment and serve to increase the capacity of the machine for special tabulating work of the character indicated.

I claim:

- 15 1. In a mechanism of the class described, in combination with adding wheels and means for actuating the same, a transversely movable paper carriage, a cam on the paper carriage, a disabling train of mechanism 20 adapted, when actuated by the cam, to disable the operation of the adding wheels, and normalizing devices adapted, when adjusted, to block the transmission of movement through the disabling train, and permit idle movement of a portion of said train 25 only by the action of the cam, substantially as described.
2. In a mechanism of the class described, in combination with adding wheels and means for actuating the same, a transversely movable paper carriage, a cam carried by the carriage, yieldably connected pivotally mounted arms adapted to be rocked by the cam, connections between said arms and the adding wheel actuating means for disabling the latter when the arms are rocked by the cam, and normalizing devices for blocking the movement of one of the yieldably connected arms whereby the other arm will 30 move idly when actuated by the cam without imparting disabling movements to the adding wheel actuating devices, substantially as described.
3. In a mechanism of the class described, 35 in combination with adding wheels and means for actuating the same, a transversely movable paper carriage, a cam carried by the carriage, yieldably connected pivotally mounted arms adapted to be rocked by the cam, connections between said arms and the adding wheel actuating means for disabling the latter when the arms are rocked by the cam, normalizing devices for blocking the movement of one of the yieldably connected arms whereby the other arm will 40 move idly when actuated by the cam without imparting disabling movements to the adding wheel actuating devices; a platen carried by the carriage, line spacing devices for rotating the platen, and connections between the normalizing devices and the line spacing devices for disabling the latter when said normalizing devices are adjusted to disable the adding wheels, substantially as 45 described.

4. In a mechanism of the class described, the combination with adding wheels and means for actuating the same to add and to subtract, a transversely movable paper carriage, connections between the paper carriage and the means for effecting a subtracting movement of the adding wheels adapted to be actuated when the carriage is in a pre-determined position of adjustment, said means including a cam on the paper carriage, a rock shaft provided with an arm adapted to co-act with said cam, and a swinging arm on the shaft for imparting movements to the subtraction actuating train, and a subtraction key connected with 50 said subtraction train to provide by a lost motion connection for direct manual actuation thereof, substantially as described.

5. In a mechanism of the class described, the combination with adding wheels and means for actuating the same to add and to subtract, a transversely movable paper carriage, a cam carried thereby, an arm engaging said cam, a rock shaft on which said arm is adjustably mounted, and means actuated by the rocking of said shaft for effecting a subtracting adjustment of the adding wheels, the arm being adjustable to a position of non-engagement with the cam, substantially as described.

6. In a mechanism of the class described, the combination with adding wheels and means for actuating the same to add and to subtract, a transversely movable paper carriage, a cam carried thereby, an arm engaging said cam, a rock shaft on which said arm is adjustably mounted, means actuated by the rocking of said shaft for effecting a subtracting adjustment of the adding wheels, the arm being adjustable to a position of non-engagement with the cam, and a subtraction key connected with the aforesaid means for effecting subtraction and adapted to operate said means independently of the 100 said cam, substantially as described.

7. In a mechanism of the class described, the combination with adding wheels and means for actuating the same to add and to subtract, a transversely movable paper carriage, a cam carried thereby, an arm engaging said cam, a rock shaft on which said arm is adjustably mounted, means actuated by the rocking of said shaft for effecting a subtracting adjustment of the adding wheels, the arm being adjustable to a position of non-engagement with the cam, and a subtraction key connected by a lost motion connection with the aforesaid means for effecting subtraction and adapted to operate said means independently of the said cam, substantially as described.

8. In a mechanism of the class described, the combination of adding wheels and means for actuating the same, a transversely movable paper carriage provided with a rotat-

- able platen, means for disabling the operation of the adding wheel actuating means, means for rotating the platen, means for disabling the operation of the platen rotating 5 means, a slide plate adapted to concurrently actuate both of said disabling means, devices actuated by the arrival of the carriage at a predetermined point for moving said slide plate to disabling position, and adjustable 10 normalizing means adapted in one position to block the movements of the slide plate, substantially as described.
9. In a machine of the class described, the combination of adding wheels and means for actuating the same, a transversely movable paper carriage provided with a rotatable platen, means for disabling the operation of the adding wheel actuating means, means for rotating the platen, means for disabling the operation of the platen rotating means, a slide plate adapted to concurrently actuate both of said disabling means, devices actuated by the arrival of the carriage at a predetermined point for moving said 25 slide plate to disabling position, and an adjustable normalizing slide plate lying adjacent to the first mentioned slide plate and adapted, when moved to a predetermined position, to block the movements of the first 30 mentioned slide plate, substantially as described.
10. In a mechanism of the class described, the combination of adding wheels and means for actuating the same, a transversely movable paper carriage provided with a rotatable platen, means for disabling the operation of the adding wheel actuating means, means for rotating the platen, means for disabling the operation of the platen rotating means, a slide plate adapted to concurrently actuate both of said disabling means, devices actuated by the arrival of the carriage at a predetermined point for moving said 35 slide plate to disabling position, adjustable normalizing means adapted in one position to block the movements of the slide plate, an escapement for the carriage, and a normalizing lever for disabling the operation of said escapement means and for simultaneously moving the normalizing slide plate to position to block a disabling movement of the disabling slide plate, substantially as described.
11. In a mechanism of the class described, the combination of adding wheels and means for actuating the same, a transversely movable paper carriage provided with a rotatable platen, means for disabling the operation of the adding wheel actuating means, means for rotating the platen, means for disabling the operation of the platen rotating same, a slide plate adapted to concurrently actuate both of said disabling means, devices actuated by the arrival of the carriage at a predetermined point for moving 40 45 50 55 60 65
- said slide plate to disabling position, and adjustable normalizing slide plate lying adjacent to the first mentioned slide plate and adapted, when moved to a predetermined position, to block the movements of the first 70 75 80 85 90 95 100 105 110 115 120 125 130 mentioned slide plate, an escapement for the carriage, and a normalizing lever for disabling the operation of said escapement means and for simultaneously moving the normalizing slide plate to position to block a disabling movement of the disabling slide plate, substantially as described.
12. In a mechanism of the class described, the combination of adding wheels and means for actuating the same, a transversely movable paper carriage provided with a rotatable platen, means for disabling the operation of the adding wheel actuating means, means for rotating the platen, means for disabling the operation of the platen rotating means, a disabling device for concurrently actuating both of said disabling means, said device being actuated by the arrival of the carriage at a predetermined point, a normalizing blocking device adapted, when moved to a predetermined position, to block the movements of said disabling device, an escapement for the carriage, and a normalizing lever for disabling the operation of said escapement device and for simultaneously moving the blocking device to position to block a disabling movement of the disabling device, substantially as described.
13. In a mechanism of the class described, the combination of adding wheels and means for actuating the same, a transversely movable paper carriage provided with a rotatable platen, means for disabling the operation of the adding wheel actuating means, means for rotating the platen, means for disabling the operation of the platen rotating means, a disabling slide plate interposed between the adding wheel disabling means and the platen rotating disabling means, said disabling slide plate being provided on its opposite edges with engaging surfaces, devices actuated by the arrival of the carriage at a predetermined point for moving said slide plate to bring said engaging surfaces to a position to simultaneously actuate both of said disabling devices, and normalizing means adapted, when moved to predetermined position, to block the movements of the slide plate, substantially as described.
14. In a mechanism of the class described, the combination of adding wheels and means for actuating the same, a transversely movable paper carriage provided with a rotatable platen, means for disabling the operation of the adding wheel actuating means, means for rotating the platen, means for disabling the operation of the platen rotating means, a disabling slide plate interposed between the adding wheel disabling means and

the platen rotating disabling means, said disabling slide plate being provided on its opposite edges with engaging surfaces, devices actuated by the arrival of the carriage 5 at a predetermined point for moving said slide plate to bring said engaging surfaces to a position to simultaneously actuate both of said disabling devices, normalizing blocking means adapted, when moved to predetermined position, to block the movements 10 of the slide plate, an escapement for the carriage, and a normalizing lever for disabling the operation of said escapement and for simultaneously moving the blocking devices to a position to prevent a disabling movement of the disabling slide plate, substantially as described.

15. In a mechanism of the class described, the combination of adding wheels and means 20 for actuating the same to add and to subtract, a transversely movable paper carriage, a rock shaft provided near its upper end with an arm, means on the carriage for engaging and moving said arm to rock the 25 rock shaft, means actuated by the rocking

of said shaft for effecting a subtracting adjustment of the adding wheels, and a subtraction key connected with the aforesaid means by a lost motion connection for effecting subtraction and adapted to operate 30 said means independently of movements of said shaft, substantially as described.

16. In a mechanism of the class described, the combination of adding wheels and means 35 for actuating the same to add and to subtract, a transversely movable paper carriage, a vertical rock shaft located in a plane behind the paper carriage and provided near its upper end with an arm, means on the carriage for engaging and moving said arm 40 to rock the rock shaft, means actuated by the rocking of said shaft for effecting a subtracting adjustment of the adding wheels, and a subtraction key connected with the aforesaid means by a lost motion connection, 45 for effecting a subtraction and adapted to operate said means independently of movements of said shaft, substantially as described.

BRUCE H. TINGLEY.
